BUCKLE FOR GARTERS

Birdie C. Sanders, Kalamazoo, Mich.

Application June 30, 1953, Serial No. 365,116

1 Claim. (Cl. 24—199)

This invention relates to improvements in buckle for garters adapted for attachment to girdles, foundation garments and other articles of wearing apparel for supporting the hose.

Many undergarments are provided with hose supporters attached thereto, usually by stitching or any other permanent relation, for supporting the hose at the front and back of the leg. Frequently, such hose supporters break or become disengaged from the garment by pulling loose from the stitching or otherwise, and have long been recognized to be unsatisfactory for the purpose.

Moreover, hose supporters are usually provided in single types, which will be attached to the hose at the front and back thereof, but difficulty is encountered in supporting the hose in such relation that they will retain the shape thereof and position on the leg, and also will not be subject to undue strain resulting in runs due to breakage of the threads at the point of connection of the hose supporters therewith.

One garter is in front that hooks onto the stocking right above the center of the knee, and the other one is in the center back right on the seam. That way, when the woman is bending her knees the pull is so great that naturally the garter has to pull to the inside of the woman's thick part of her leg. By having the garters pull toward the inside of her leg, or on the outside that makes trouble. It also makes trouble with the back seam. It also makes a lot of runs in the hose. It cuts in the leg and could cause varicose veins because it stops the circulation.

It also wears out the garters on the girdle, and makes it difficult to sew it by hand or with a regular sewing machine. That stops the give to the elastic. The result is very thick and clumsy. It makes it very uncomfortable to sit on.

One object of this invention is to overcome the foregoing objections to hose supporters provided heretofore and to improve the construction of hose supporters provided for this purpose.

A further object of the invention is to provide for the ready detachment of a hose supporter from an undergarment without serious danger of its pulling loose in service and which does not require stitching to connect the hose supporter with the undergarment.

Another object of the invention is to provide a buckle which may be attached or connected in any way with a hose supporter or other portion of a garment for detachable connection with an undergarment or another portion thereof, for connecting the same together, which buckle may be manufactured inexpensively, and provides an efficient detachable connection which nevertheless will not become accidentally disengaged from the other portion, except when desired.

Still another object of the invention is to provide a buckle which may be attached to a hose supporter without requiring stitching thereto, and yet will be maintained in secure relation on the hose supporter for detachable engagement with a loop on an undergarment, whereby the

2

supporter may be connected thereto readily and simply whenever desired.

Still another object of the invention is to improve the construction of a hose supporter which will provide a twin connection with the hose by laterally diverging sections connected to a suspended portion attached to the undergarment, that will serve to maintain the hose effectively in place on the leg without danger of shifting or causing strain on the fabric that may result in a run.

10 These objects may be accomplished according to certain embodiments of the invention, which are set forth in the accompanying drawings in which:

Fig. 1 is a perspective view showing the invention applied to an undergarment;

15 Fig. 2 is an enlarged side elevation of the connected portions of the undergarment and hose supporter;

Fig. 3 is a view at right angles thereto, partly in section;

20 Figs. 4, 5 and 6, are side elevations of buckle members embodying this invention; and

Fig. 7 is a front elevation of the hose supporter.

The invention is shown in connection with an undergarment generally designated by the numeral 1, which is illustrated as a foundation garment, although it will be understood that the invention may be used on any suitable undergarment, girdle, or the like, as desired.

Extending downwardly from the undergarment 1 is an elongated hose supporter strip 2, usually of elastic webbing, although any suitable material may be used therefor. This elongated strip 2 forms a garter strap, the length of which will depend upon the character of the undergarment to which it may be attached, and the length of the hose adapted for connection therewith and to be supported thereby. It may be either long or short, therefore, and only one size is illustrated as an example, with the understanding that other sizes and lengths can be used as desired.

At the lower end of the garter strap 2 is secured a loop 3, shown as substantially triangular and having a crossbar 4 at the upper side thereof, and downwardly diverging sides 5 and 6, joined to the crossbar to provide said triangular shape. The sides 5 and 6 are shown as straight respectively, although they may be curved somewhat in the manner of a D-ring if preferred.

45 Straps 7 and 8 extend downwardly from the sides 5 and 6 in diverging relation, as shown in Figs. 1 and 7, which straps may also be in the form of elastic webbing, if desired. The upper ends of the straps 7 and 8 are permanently attached to the sides of the loop 3, as by folding over and stitching, while the lower ends thereof are free and preferably have loop clasps 9 attached thereto for connecting the straps 7 and 8 with the hose.

50 The twin garter straps 7 and 8 preferably are used at the front of the undergarment and should be connected with the hose at opposite sides of the knee so as to balance the pull applied to the hose to relieve the latter of undue strain, which otherwise may cause runs.

If preferred, a single strap may be used on the garter strap 2, especially at the back of the garment, in place of the twin straps 7 and 8. Suitable adjusting means may be provided for the length thereof, as by means of a slide buckle, generally indicated at 10, and a similar slide buckle may be used, if desired, on each of the side straps 7 and 8.

55 The upper end of the garter strap 2 is preferably detachably connected with the undergarment 1, for which purpose it is provided with a buckle 11, having detachable connection with a loop 12 secured to the undergarment 1, and depending from the lower edge thereof at the point of connection of the hose supporter thereto. In the example illustrated in the drawings, the loop 12 is provided by a

strip of fabric of secure material, folded back upon itself, and applied in embracing relation about the lower edge portion of the garment 1, to which it may be secured as by stitching 13. This leaves a loop projecting below the lower edge of the undergarment, open at opposite ends for detachable engagement by the buckle 11, whereby the hose supporter may be detachably connected with the undergarment 1 and separated therefrom when desired.

The buckle 11 may be stamped out of suitable material, molded or otherwise formed, and any suitable material may be used for the purpose, as sheet metal, plastic, or the like. A suitable coating, as enamel, preferably is applied thereover to give a smooth surface and neat appearance, although this will not be required if the material when formed has the desired shape and appearance.

As shown in Fig. 4, the buckle 11 is made substantially rectangular, with parallel arms 14 and 15, joined together at one end by a connecting portion 16, while the opposite ends are separated with an entrance opening 17 therebetween. The arm 14 forms a bar over which the upper end of the garter strap 2 is folded and stitched in secure relation for permanent attachment of the buckle 11 to the garter strap. The free end of the arm 14 is turned back upon itself, with an elongated finger section 18, which preferably forms a longitudinal arc along the length of the arm 14 and extends throughout at least one-half of the length of said arm. This finger portion 18 thus overlies the loop formed in the garter strap 2, allowing the latter to be slipping under the finger portion between the latter and the arm 14, but effectively preventing accidental separation thereof in service. The longitudinal curvature of this finger portion 18 facilitates the introduction of the buckle into the loop in the garter strap and increases the holding effect of the buckle thereon when in place, tending to retard the likelihood of detachment in service.

The arm 15 forms a bar which may be inserted through the loop 12 on the undergarment, and has an inturned end portion 19, separated from the finger portion 18, with the opening 17 therebetween. This allows the buckle to be attached readily to the loop 12 by introduction of the loop through the opening 17 along the arm 15, as the latter is introduced through the loop, after which the backturned end portion 19 retains the buckle on the loop. At the same time, the buckle may be disengaged readily therefrom, when replacement is desired.

Other sizes or shapes of buckles may be used, some of which are illustrated in Figs. 5 and 6, either for attachment to garter straps or other garment portions. In the example illustrated in Fig. 5, instead of a rectangular buckle as shown in Fig. 4, this is more nearly triangular in shape due to the lengthened side 16' and the converging relation of the bar 14' with respect to the bar 15'. Such shape may be desirable, especially when a converging relation of the garter strap is desired, as indicated at 7 and 8 in Fig. 7, or where the attachment is used on the side of the undergarment with a lateral pull on the garter strap.

Another modification is shown in Fig. 6 in which the buckle 11' is attached rigidly to a loop member 20 of a hose fastener, either in one piece therewith or secured rigidly together. This may provide a connection between the hose clasp and the garter strap for detachment and separation when desired.

It will be apparent from the above that the detachable connection provided by the buckle to a portion of the undergarment formed with a loop adapted to receive the buckle, enables the hose supporter, or other garment member, to be detachably connected therewith for ready separation or replacement without requiring stitching or

other special fasteners. Moreover, in the event of breakage of the clasp, strap or other member, another may be substituted therefor easily and quickly. When in place, the buckle will hold the member securely to the undergarment, without danger of accidental separation, although permitting detachment when desired. The buckle holds the garter strap to the undergarment without danger of swaying and maintains the proper degree of tension on the hose as well as securing the latter effectively to the undergarment.

10 The twin attachment provided by the diverging garter straps 7 and 8 maintains a balanced attachment on the hose, which will distribute the strain uniformly to opposite sides of the knee and thereby tend to prevent such strain as may cause a run in the fabric.

15 The twin garters give the woman comfort and even distribution as they will take in half of the hose in front of the knee and she will have freedom to bend her knees in any position. It will save on hose and on girdles. Her seams will always be in place where they should be. It will save her from getting varicose veins, too.

20 The twin garters may be made in two styles. One style will be for the tall woman; it will start with the single garter 2 joining into the twin garters 7 and 8. They will be detachable and adjustable for any height person.

25 The second twin garters will be made detachable and adjustable starting the twin garters right from the twin buckle 11 and the two garters that make up the twin may be also adjustable.

30 The third garter will be a single garter for the back also could be used in front if desired. It will be detachable and adjustable for any height person. These garters will be very good for evening girdles, corselets, or garter belts.

35 While the invention has been illustrated and described in certain embodiments, it is recognized that variations and changes may be made therein without departing from the invention set forth in the claim.

I claim:

40 A buckle for attachment of a hose supporter comprising a single length of material of uniform width and thickness throughout its length, said length of material including a pair of parallel arms joined together at one end by a connecting portion extending directly between the adjacent ends of said arms with a smooth and uniform cross-sectional area throughout its length, each of said arms having a backturned portion on the opposite end thereof extending substantially parallel with said arm throughout a substantial portion of the length thereof, one of said backturned portions extending throughout substantially one-half the length of the arm thereof with the free end thereof spaced freely from the connecting portion throughout approximately one-half the length of said arm.
